CLAIM

I claim the ornamental design for a microphone with stand, as shown and described.

DESCRIPTION

FIG. 1 is a perspective view of a microphone with stand; FIG. 2 is a top view of the microphone with stand of FIG. 1;

FIG. 3 is a bottom view of the microphone with stand of FIG. 1;

FIG. 4 is a side view of the left side of the microphone with stand of FIG. 1;

FIG. 5 is a side view of the right side of the microphone with stand of FIG. 1;

FIG. 6 is a front view of the microphone with stand of FIG. 1; and,

FIG. 7 is a rear view of the microphone with stand of FIG. 1.

The broken lines depict environment that are for illustrative purposes only and form no part of the claimed design.
